PLATE BURNER FOR PHOTOENGRAVING

Frank T. Powers, Glen Cove, N. Y.; Frank T. Powers, Jr., and John M. Powers, executors of said Frank T. Powers, deceased, assignors to Powers Photo Engraving Company, a corporation of New York

Application September 30, 1947, Serial No. 777,089

3 Claims. (Cl. 263—2)

1

The present invention relates to a novel and improved plate burner or burning-in stove for use in photoengraving.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Figure 1 is a side elevation, with parts broken away, of the present preferred and illustrative embodiment of the invention;

Figure 2 is a sectional view taken on the line 2—2 of Figure 1;

Figure 3 is a fragmentary detailed section taken on the line 3—3 of Figure 1; and

Figure 4 is a circuit diagram showing the electrical connections as used in the illustrative embodiment.

The present invention has for its object the provision of a novel and improved burning-in stove for photoengraving use which gives greater uniformity of heating of the plate than has heretofore been possible. A further object of the invention is the provision of a stove for photoengraving use which provides for different rates of heating of the plate, and in which the plate need not be manipulated during the time of heating. Still another object of the invention is the provision of an automatic plate burner in which the plate is constantly moved with respect to the source of heat during the heating operation so that the plate is uniformly heated notwithstanding the fact that the source of heat may not distribute the heat uniformly.

In accordance with the present invention, there is provided a plate carrier adapted to receive a photoengraving plate such as a halftone or line engraving, which carrier is movable into and out of a casing, and while within the casing, the plate is subjected to relatively intense heat so as to burn-in the exposed and developed photo-sensitive resist, usually bichromated gelatin, or to melt the etching powder which has been applied to the partially etched plate, this etching powder

2

usually being dragon's blood or some equivalent resin. Various sources of heat may be used but I prefer to use two series of gas burners, inasmuch as gas is usually more economical than infra-red lamps or other sources of heat which can be used for this purpose.

Means are provided for automatically turning on the gas as soon as the plate carrier has been moved into the casing and into heating position, 10 and other means are provided for constantly reciprocating the plate carrier while it is within the casing and in heating position so that the heat is uniformly distributed over the plate, and no excessive heating of the metal takes place. 15 These reciprocating means are optionally operated so that the plate carrier may be reciprocated or not during the heating operation, and the heating means preferably include selectively operable means so that a portion of the heating means are in operation when the plate reciprocating means are operated, and additional heating means may be optionally brought into operation when the reciprocating means are not used. Means are also provided for engaging and 20 disengaging the reciprocating means with respect to the plate carrier so as to permit the operator to withdraw the plate carrier and the plate carried by it from the casing when the heating operation has been completed.

30 Referring now in detail to the accompanying drawings, which illustrate a typical and preferred embodiment of the present invention, there is provided a casing 10 connected to an exhaust vent 11. Within the casing and at a convenient 35 horizontal level are two series of gas burners 12 and 13 of the type ordinarily used in burning-in stoves, these burners being distributed over the horizontal area of the casing so that the flames of each set are substantially uniformly spaced. 40 The burners 12 and 13 are fed with gas from the supply line 14 through electromagnetic valves 15 and 16, these valves serving to open the line to full intensity while they are energized, and to close the line when deenergized so to reduce 45 the flame until it is just sufficiently large to keep the burners lit, the gas then being supplied through the by-passes 15' and 16'. The series of burners 12 and 13 are preferably arranged parallel to each other and across the path of movement of the plate as it is moved into or out of the casing. The burners 12 and 13 are supported on rails 16 extending from one side wall 18 to another of the casing, and in the case of gas burners the source of heat is prefer-

ably positioned below the plate and its path of movement.

The plate carrier comprises a pair of side rails 20 which are connected at their ends by rods 22 and 23, as well as by intermediate rods 24, the intermediate rods serving to support a series of thin parallel metal straps 25 which are mounted edgewise and whose upper surfaces form a support for the plate to be heated or burned-in. At its forward end the plate carrier is provided with rollers 27 which are rotatably mounted on the ends of rod 23 and run in channels 29 which are horizontal, parallel to each other and supported at their ends by the vertical angle members 31 at the corners of the casing. Means are provided for supporting the outer or rearward end of the plate carriers, and comprise the links 32 which are pivotally mounted on the ends of rod 22, the lower ends of the links being connected by a rod 34 at the ends of which are rollers 36 which slide in the vertically disposed channels 38.

Links 32 are pivotally connected to links 46 which are mounted on brackets 48 secured to the wall 18, and are pivotally connected to the links 32 by pivot 50.

Means are also provided for preventing the carriage from moving in too rapidly into the heating chamber, and for this purpose the lower cross rod 34 is engageable with the outer ends of pivotally mounted levers 39, the inner ends of which are pivoted at 40 on brackets 41. Intermediate their ends levers 39 are connected to tension springs 43 the upper ends of which are secured to eyes 44 mounted in the casing wall 18. As the carrier approaches its forwardmost position, its speed is checked by the tensioning of spring 43.

The plate carrier thus constructed may be easily moved into and out of the stove casing so as to bring a plate supported by the strips 25 directly above the heating means 12 and 13, while link 46 serves to support the outer end of the casing and lever 39 serves to prevent a too rapid movement of the plate carrier into the casing, the action of spring 43 being such as to slow the plate carrier as it moves into the casing.

Means are provided for continually reciprocating the plate carrier while it is in burning-in position, and these means preferably comprise an electric motor 60 driving crank 61 through speed reduction gearings 62. Crank 61 is arranged on an axis transverse to the movement of the plate carrier, and is a variable throw crank of conventional form connected to adjustable link 64. The other end of link 63 is pivotally connected to an adjustable bracket 66 which can be moved to different positions along the vertical rod 67 and secured in the desired position by tightening set screw 68. The upper end of the rod 67 is connected to the inner end of link 70 which extends far enough so that the slot 71 at its outer end may engage with rod 72 which extends between and is connected to links 32. Link 70 is supported and guided by means of antifriction roller 74 which is rotatably mounted on bracket 75 which in turn is carried by the support 76 fastened to the side walls of the casing. Resilient means such as spring 78 connecting link 70 with an eye 79 are provided for holding the link 70 down and in engagement with rod 72.

As motor 60 operates, the crank 61 slowly rotates causing a corresponding reciprocation of the link 70 which is imparted to the plate carrier so as to move the plate carried thereby back and forth over the banks of gas flames heating the plate.

Means are provided for manually controlling the supply of power to the motor 60 and the supply of gas through valve 15 to the bank 12 of burners and also for simultaneously engaging link 70 with the plate carriage so that the motor 60 is energized, gas burners brought to full intensity, and the link connection for driving the plate carriage are all simultaneously effected by operation of a single manual control. As embodied there is provided an eccentric 80 secured to shaft 81, journaled in the opposite side walls 82 of the casing 10, the eccentric serving in one position to lift the link 70 sufficiently so that its slotted end 71 is raised out of the path of rod 72, or alternatively to lower the link 70 so as to establish the driving connection between crank 61 and the plate carriage. At one outer end of shaft 81 is provided another eccentric 83 so related to eccentric 80 that motor switch 85 is closed as the link 70 is lowered into driving position, while the other end of shaft 81 is provided with a hand lever 86 by which the shaft 81 and its eccentrics 80 and 83 may be conveniently moved from one position to the other.

Means are also provided for optionally energizing the electromagnetic valves 15 and 16 so that the burners 12 and 13 are brought to full intensity when it is desired to exercise manual control over the burning-in process. For this purpose, a switch 88 is provided on the rear wall 18 of the casing, and is engaged by bar 23 when the plate carrier is moved completely into the casing. Movement of the plate carrier to this position closes switch 88 so as to open valves 15 and 16 completely and thereby supply a full flow of gas to the burners 12 and 13.

Figure 4 of the drawings illustrates diagrammatically the electrical connections of the various electrical parts used in the preferred embodiment. As illustrated, power is derived from a suitable source 90 and is supplied through the main switch 91 to conductors 92 and 93. For convenience in observing the interior of the machine and the extent of melting or burning-in of the resist on the plate, a lamp 94 is provided within the casing and is supplied with power through switch 95 from the conductors 92 and 93. When the manual lever 86 has been swung to close switch 85, current is supplied to motor 60 through switch 85 from the conductors 92 and 93, and simultaneously the coil 96 of relay 97 is energized so as to connect contacts 98 and 99 by bridge 100 thereby supplying current to the coil 101 of the electromagnetic valve 15, thereby increasing the flow of gas to the burners 12 so that these burners deliver their full heat while the motor 60 is driving the plate carrier.

When the plate carrier is moved fully into the casing, switch 88 is closed and thereby current is supplied through it from conductors 92 and 93 through the winding 102 of electromagnetic valve 16, and valve 15 is opened by current supplied to coil 101 through bridge 100 which is then in contact with contacts 103 and 104, inasmuch as coil 96 of relay 97 is not energized. With both valves 15 and 16 fully opened, burners 12 and 13 are thus automatically brought to full heat whenever the carriage is manually moved to its innermost position.

The plate burner of the present invention thus provides a single burning-in stove by which a photoengraved plate, such as a line engraving which has been partially etched and powdered, can be intensely heated under manual control, the burners being automatically brought to full

heating position manually by moving the carriage into heating position, and also provides a stove which is adapted for the slower and more uniform degree of heating required for the burning-in of the developed bichromated resist, such as is used in the halftone engraving process.

The invention in its broader aspects is not limited to the specific mechanisms shown and described but departures may be made therefrom within the scope of the accompanying claims without departing from the principles of the invention and without sacrificing its chief advantages.

What is claimed is:

1. A photoengraving stove including in combination a source of heat, a support to position a plate to be heated by said source, means for moving said support and plate back and forth relative to said source while the plate is being heated so as to distribute the heat on said plate, a motor, a crank and link interconnecting the motor and support the link being detachably engageable with the support, a manually actuated eccentric controlling the engagement and disengagement of the link with the support, and means controlling said source of heat and actuated in common with the eccentric so that the link is positioned for engagement with the support as the heat is turned on.

2. A photoengraving stove including in combination a source of heat, a support to position a plate to be heated by said source, means for moving said support and plate back and forth relative to said source while the plate is being heated so as to distribute the heat on said plate, a motor, a crank and link interconnecting the motor and support the link being detachably engageable with the support, a control means for the source of heat, and a handle for moving said control means and simultaneously positioning the

30
35
40

link for driving engagement with the plate support.

3. A photoengraving stove including a plurality of sources of heat, a support to position a plate to be heated by one or more of said sources mounted for horizontal movement relative to said sources, a motor, means interconnecting said motor and support for reciprocating the latter while the plate is heated said means including a crank connected to said motor and a link connected to said crank and detachably engageable with said support, control means actuated by movement of the support to a particular position for energizing all of said sources, and additional manual means for alternatively energizing a portion of said sources while the support is horizontally moved, said manual means comprising common means for energizing the motor, engaging said link with said support, and energizing a portion of the sources of heat, said common means including an eccentric positioning the link for engagement with the support.
